UNITED STATES PATENT OFFICE.

JOHN MEHL, JR., OF JERSEY CITY, NEW JERSEY.

DESIGN FOR A COVER FOR POCKET-BOOKS OR CARD-CASES.

SPECIFICATION forming part of Design No. 28,174, dated January 18, 1898.

Application filed December 14, 1897. Serial No. 661,903. Term of patent 3½ years.

To all whom it may concern:

Be it known that I, JOHN MEHL, Jr., a citizen of the United States, residing at Jersey City, in the county of Hudson and State of New Jersey, have invented and produced a new and original Design for the Covers of Pocket-Books or Card-Cases, of which the following is a specification, reference being had to the accompanying drawings, forming 5
10 a part thereof, in which—
Figure 1 is a plan view of a cover for a pocket-book or a card-case embodying the features of my design, and Fig. 2 is a section on the line 2 2 of Fig. 1.
15 The design consists in the embossed panel

A at an end of the cover, the inner edge of the panel being provided with a bead *a*. The central portion *b* of the inner edge of the panel is straight and joins at its ends compound curved portions *b'* and *b''*, the convexed sections of the compound curved lines *b'* and *b''* extending to opposite sides of the cover. 20

I claim—

The design for a cover for pocket-books and 25 card-cases herein shown and described.

JOHN MEHL, JR.
